US00D997468S

(12) **United States Design Patent** (10) **Patent No.:** **US D997,468 S**
(45) **Date of Patent:** **** Aug. 29, 2023**

(54) **PET COMB**

(71) Applicant: **Dongguan Chuangjie Electronic Technology Co., Ltd**, Dongguan (CN)

(72) Inventor: **Jie Wang**, Dongguan (CN)

(**) Term: **15 Years**

(21) Appl. No.: **29/873,562**

(22) Filed: **Apr. 3, 2023**

(30) **Foreign Application Priority Data**

Oct. 12, 2022 (CN) 202230673000.3

(51) **LOC (14) Cl.** **30-99**

(52) **U.S. Cl.**

USPC **D30/159**; D30/158

(58) **Field of Classification Search**

CLAIM

The ornamental design for a pet comb, is as shown and described.

DESCRIPTION

FIG. 1 is a perspective view of a pet comb showing my new design;

FIG. 2 is the other perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines illustrate portions of the pet comb that form no part of the claimed design.

1 Claim, 7 Drawing Sheets
